JOHN L. WARREN, OF DETROIT, MICHIGAN, ASSIGNOR TO GEORGE HARGREAVES AND SAMUEL HARGREAVES, OF SAME PLACE.

Letters Patent No. 101,329, dated March 29, 1870.

IMPROVEMENT IN OVAL-TURNING TOOL.

The Schedule referred to in these Letters Patent and making part of the same

To whom it may concern:

Be it known that I, JOHN L. WARREN, of Detroit, in the county of Wayne, and State of Michigan, have invented a new and useful Improvement in Lathes for Turning Ovals; and I do hereby declare that the following is a true and accurate description thereof, reference being had to the accompanying drawings and to the letters of reference marked thereon, and being a part of this specification.

Figure 1 is a front elevation of my invention.

Figure 2 is a perspective view from the rear side.

Figure 3 is a plan view of the revolving face-plate, upon which the gibbed frame vibrates.

Figure 4 is an elevation of the inner side of my cutter-head.

Like letters indicate like parts in each figure.

The nature of this invention relates to an improved construction of lathes for turning oval and circular frames in wood; and consists in a metallic cap secured to the top of the cutter-head, covering the knives, and conforming to the outline of their cutting edges, yet leaving a space between said cap and said knives for the passage of shavings, and in combination therewith, the arrangement of the knives upon the cutter-head.

In the drawings—

A represents a proper frame, having two standards B B' in proper bearings, in which is journaled the mandrel C, rotated in a convenient manner, and carrying on its front end the quadrangular slide D; rigidly secured thereto is a circular disk of metal provided with a horizontal slot through which projects the mandrel C. It is also provided with smaller horizontal slots e, through which pass set-screws e' securing it to the standard B, and allowing it a lateral adjustment with relation to the mandrel.

E is a face-plate, provided with dovetail ways f, which embrace the beveled edges of the slide D. It is also provided with gibbs f', which embrace the periphery of the disk F. Onto the front projecting edges of the face-plate the board, from which a frame is to be cut, is dogged or otherwise secured.

The operation of the mechanism just described is to produce an eccentric movement of the wood chucked on the face-plate, which is effected by setting the center of the disk F away from that of the mandrel; the rotation of the face-plate being effected by the man-

dreli, it is compelled by its gibbs to travel around the disk, its ways f sliding freely on the slide D in its gyration, and thus describe a perfect oval at any point on the face of the wood; by setting the circular disk to or from the mandrel, ovals of any degree of eccentricity may be described; by making the center of the disk coincident with that of the mandrel, a circle would be produced.

G is a slide-rest on the front of the frame, carrying the cutter-head H, to which are bolted the cutters or knives I, the peculiarity of which is that their cutting edges are all on one radial line, as shown in fig. 4, rendered necessary from the fact that if the knives were made as are ordinary molding-irons, with one point varying in height with another, a confusion of ovals would be the result, the block describing at each point of the cutting edge an oval whose radius differs from that of each other point of depression or elevation in the knife, consequently there would be as many different ovals described as there are elevations or depressions in the knife.

J is a metallic cap conforming in outline to the contour of the knives, whose edges it nearly covers, and is secured at its ends by proper bolts to the top of the cutter-head; the small space between its lower edge and the edge of the knives forms a "throat" through which passes the shavings taken from the wood.

The object of the cap is to regulate the thickness of the shaving taken from the wood; without it the knives would dig into the wood, taking off chips instead of shavings, resulting in the spoiling of the frame.

By the employment of the knives of the peculiar construction described, and the use of the cap, perfect frames of uniform size are produced at one operation from rough boards, without previous sawing or shaping.

What I claim as my invention, and desire to secure by Letters Patent, is—

1. The metallic cap J, as described, and operating as and for the purpose set forth.
2. In combination with the metallic cap J, the knives I, arranged upon the cutter-head as described, and operating as and for the purpose set forth.

JOHN L. WARREN.
